UNITED STATES PATENT OFFICE

106,662

DESIGN FOR A VACUUM CLEANER CASING

Lurelle Guild, Darien, Conn., assignor, by mesne assignments, to Electrolux Corporation, Dover, Del., a corporation of Delaware

Application March 25, 1937, Serial No. 68,404

Term of patent 14 years

To all whom it may concern:

Be it known that I, Lurelle Guild, a citizen of the United States of America, residing in Darien, Connecticut, have invented a new, original, and ornamental Design for a Vacuum Cleaner Casing, of which the following is a specification, reference being had to the accompanying drawings, forming part thereof;

Fig. 1 is a side view of a vacuum cleaner casing showing my new design;

Fig. 2 is a top view of the vacuum cleaner casing shown in Fig. 1;

Fig. 3 is an end view of the vacuum cleaner casing as seen from the left in Fig. 1;

Fig. 4 is an end view of the vacuum cleaner casing as seen from the right in Fig. 1; and

Fig. 5 is a perspective view of the vacuum cleaner casing shown in the preceding figures.

I claim:

The ornamental design for a vacuum cleaner casing, as shown.

LURELLE GUILD.
